CLAIM

The ornamental design for a base frame for a racing simulator cockpit, as shown and described.

DESCRIPTION

FIG. 1 is a front perspective view of a base frame for a racing simulator cockpit showing my new design;

FIG. 2 is a rear perspective view thereof;

FIG. 3 is the front perspective view of FIG. 1 which includes an illustrative example of a racing simulator cockpit shown in broken lines;

FIG. 4 is a rear perspective view of the elements thereof;

FIG. 5 is left side view of the elements thereof;

FIG. 6 is right side view of the elements thereof;

FIG. 7 is rear view of the elements thereof;

FIG. 8 is front view of the elements thereof;

FIG. 9 is a top plan view of the elements thereof; and,

FIG. 10 is bottom plan view of the elements thereof.

The broken lines showing the bottom of the oval legs, in FIG. 10, depict portions of the base frame for racing simulator cockpit and form no part of the claimed design.

(Continued)

The remaining broken lines in the drawings depict environmental structure and form no part of the claim.
